BEVERAGE DISPENSING DEVICE

Charles H. Heitman, Jeffersonville, N. Y.

Application October 8, 1937, Serial No. 167,998

6 Claims. (Cl. 62—89)

This invention relates to devices for dispensing liquids such as beverages.

More specifically my invention relates to a beverage dispensing unit wherein the beverage or beverages may be placed in a plurality of containers, the containers placed in the dispensing unit, and the beverages withdrawn directly from the containers, thus ensuring against contamination of the beverages.

10 The prime object of my invention is to provide for the dispensation of cooled and uncooled beverages under conditions of absolute sanitation at all times.

15 A further object is to provide for the inclusion within the unitary structure of a liquid dispenser remote from the cooling zone and from which liquid at room temperature may be directly withdrawn.

Another object is to provide a device in which 20 a refrigerating compartment is provided for the reception and cooling of articles other than the liquid being dispensed.

Another object is compactness of structure, 25 simplicity and cheapness of structure, and the provisions of a device which will not be likely to get out of order.

With these and other objects in view I shall proceed to a more detailed description of my invention in connection with the accompanying 30 drawing, in which:

Fig. 1 is a front elevational view of the unitary cabinet embodying my invention;

Fig. 2 is a sectional view taken on the line 2—2 of Fig. 1;

35 Fig. 3 is a side view partially in a vertical section through the cabinet and one of its containers, and

Fig. 4 is an end view of one of the containers which I employ.

40 Like characters of reference indicate like parts throughout the several views of the drawing.

Referring to the drawing, the unitary cabinet embodying one exemplification of my invention is designated by the reference character 45 1. This cabinet may be said to have three compartments in the top portion thereof, designated respectively 2, 3 and 4, all of which are enclosed by an outer wall 5, preferably constructed of sheet metal, which surrounds the three said

50 compartments with the exception of the top thereof which latter is provided with a hinged cover 6 common to all three compartments. An inner wall 7, also preferably of sheet metal, and spaced from the wall 5, is provided. This wall 55 5 encloses compartments 2 and 3 but does not

extend about the outer wall of the compartment 4, for a reason which will hereinafter appear.

The space provided between the two walls 5 and 7 is filled with any suitable insulating material 8, such for instance as rock wool.

5 The compartments 2 and 4 have therein rectangular boxlike receptacles, 2' and 4', respectively, open at the top and within which are operatively disposed the rectangular containers or cans 9 and 10 which are identical in every respect so as to be interchangeable, a front end elevation of which is shown in Fig. 4. These containers or cans are provided with taps or faucets 11 located in the front end thereof at the bottom at a point to the left of the center, as shown in the drawing. At the top thereof the cans are provided with handles 12 for facility in lowering and raising them to and from operative position within their compartments, and ports 12' for filling the cans are shown in the top 20 thereof.

In the upper front face of the cabinet two slots 13 are provided through which when cans 9 and 10 are in operative position the taps or faucets project. Each of these slots is provided 25 with a filler strip 14, one of which is shown in dotted lines partially retracted from its slot in Fig. 1.

In practice the strips 14 are withdrawn entirely from the slots 13, whereupon the cans 9 30 and 10, with their faucets projecting through the slots, are lowered into operative position in their respective compartments 2' and 4', after which the filler strips 14 are slid into position. The lower ends of these strips are contoured so as to 35 snugly fit the upper part of the base of the faucets.

These filler strips are shown as hollow metallic shells filled with a suitable insulating material. They should have a snug but easily sliding fit in 40 the slots 13 so that air will not be admitted, at least to compartment 2, and thus lower the refrigeration value.

In the bottom of compartment 3 is provided a coiled pipe 15 through which is circulated a suitable refrigerating solution, emanating from a suitable refrigerating unit (not shown) of any of the well known types, which is mounted in the base of the cabinet 1.

It will be noted that compartment 3 affords 50 a considerable space between the pipe 15 and the top of the cabinet and between the compartments 2 and 4. This space is available as a refrigerator for the reception of any article which it may be desired to keep cool. If desired this space may

also be utilized as an ice chamber by many who prefer to use ice rather than mechanical refrigeration, or when the cooler is used where power for mechanical refrigeration is not available. When this space is used as an ice chamber, the pipe 15 is commonly removed.

The walls 16 and 17 of the receptacle 2' are spaced from the surrounding walls in order that the chilled air or water, as the case may be, may 10 circulate thereabout.

Between the compartment 4, wherein the container 10 is housed in its receptacle 4', and the compartment 3, is an insulated wall 20 which prevents heat-exchange between the two compartments and accordingly the liquid in container 10 will remain at room temperature. This is desirable for the reason that many people prefer water, for instance, at a temperature higher than is commonly dispensed by water coolers 15 generally. The arrangement just described enables one to draw directly from the two faucets a mixture of chilled and unchilled liquid at the temperature desired. Obviously the container 10, if desired, may be utilized for the dispensing of 20 any liquid which preferably would not be chilled.

Beneath the two faucets is shown the usual drip-pan 21.

It will be seen from the foregoing disclosure that in the dispensing of spring or filtered or 30 otherwise purified water, the cans may be filled at a central distributing depot and distributed to the consumer in closed condition in the conventional manner, and that the cans may be mounted in their receptacles in the cabinet and water 35 drawn directly therefrom without its coming in contact with any extraneous mechanism such as an intermediate cooling coil or an intermediate reservoir.

My invention therefore provides for the dispensing of beverages to the consumer, either 40 chilled or unchilled in absolutely sanitary condition.

While I have described my invention more particularly in connection with the dispensing of water, it is obvious that it is adapted for the dispensing of any kind of liquid, and that it is admirably adapted for the dispensation of milk which is a commodity so easily susceptible to dangerous contamination.

In the foregoing description I have disclosed an 50 exemplification of my invention which employs but two dispensing units, but obviously a battery of such units for dispensing a variety of liquids or beverages may be included within a single unitary structure, all of which may be cooled by a single refrigerating unit.

I claim:

1. A liquid dispensing apparatus of the class described, comprising an enclosure having several 60 compartments, at least one of which is exposed to room temperature and is designed for the dispensation of liquid directly therefrom, and the others of which compartments are insulated against heat-exchange from the surrounding atmosphere and from said exposed compartment or compartments, and a refrigerating means in heat-exchanging relation with one or more of said other compartments.

2. A liquid dispensing apparatus of the class 70 described, comprising an enclosure having several compartments, at least one of which is exposed to room temperature, and the others of which compartments are insulated against heat-exchange from the surrounding atmosphere and

from said exposed compartment or compartments, and a refrigerating means in heat-exchanging relation with one or more of said other compartments, and liquid-containers in said exposed and insulated compartments, said liquid containers being respectively provided with individual dispensing means.

3. A liquid dispensing apparatus of the class described, comprising an enclosure having several compartments, at least one of which is exposed to 10 room temperature, and the others of which compartments are insulated against heat-exchange from the surrounding atmosphere and from said exposed compartment or compartments, a refrigerating means in heat-exchanging relation with one or more of said other compartments, and liquid-containers in said exposed and insulated compartments, said liquid-containers being respectively provided with individual dispensing means comprising integral faucets, said enclosure 20 having in a wall thereof slots through which said faucets project, and means for closing said slots.

4. A liquid dispensing apparatus of the class described, comprising an enclosure having several compartments, at least one of which is exposed to room temperature, and the others of which compartments are insulated against heat-exchange from the surrounding atmosphere and from said exposed compartment or compartments, and a refrigerating means in heat-exchanging 25 relation with one or more of said other compartments, and liquid-containers in said exposed and insulated compartments, said liquid-containers being respectively provided with individual dispensing means, one of said compartments comprising 30 a refrigeration chamber for the reception of articles other than those being directly dispensed.

5. A liquid dispensing apparatus of the class described, comprising an enclosure having several 40 compartments, at least one of which is exposed to room temperature, and the others of which compartments are insulated against heat-exchange from the surrounding atmosphere and from said exposed compartment or compartments, 45 and a refrigerating means in heat-exchanging relation with one or more of said other compartments, and liquid containers in said exposed and insulated compartments, said liquid-containers being respectively provided with individual dispensing means, one of said compartments comprising 50 a refrigeration chamber for the reception of articles other than those being directly dispensed, and a heat-insulated cover common to 55 all compartments.

6. A device of the class described comprising an enclosure having slots in one wall thereof, receptacles in said enclosure, liquid-containers in said receptacles, means for withdrawing liquid directly from said containers comprising faucets 60 which project through said slots, means for sealing said slots, at least one of said containers being exposed to room temperature, and others of said containers being insulated against heat-exchange from the surrounding atmosphere and from said 65 exposed container, refrigerating means in heat-exchanging relation with said insulated containers, an insulated cover for said enclosure, means whereby the cooling medium will circulate about said insulated containers, and a refrigeration chamber in said enclosure for articles other than those being dispensed from said containers.
